(57) **CLAIM**

The ornamental design for a hose, as shown and described.

DESCRIPTION

FIG. 1 is a perspective view of a first embodiment of a hose;
FIG. 2 is a rear elevation view of the hose shown in FIG. 1;

FIG. 3 is a front elevation view of the hose shown in FIG. 1;
FIG. 4 is a left side elevation view of the hose shown in FIG. 1;

FIG. 5 is a right side elevation view of the hose shown in FIG. 1;

FIG. 6 is a top plan view of the hose shown in FIG. 1; and
FIG. 7 is a bottom plan view of the hose shown in FIG. 1.
FIG. 8 is a perspective view of a second embodiment of a
hose;

FIG. 9 is a rear elevation view of the hose shown in FIG. 8;
FIG. 10 is a front elevation view of the hose shown in FIG. 8;
FIG. 11 is a left side elevation view of the hose shown in FIG. 8;

FIG. 12 is a right side elevation view of the hose shown in
FIG. 8;

FIG. 13 is a top plan view of the hose shown in FIG. 8; and
FIG. 14 is a bottom plan view of the hose shown in FIG. 8.

FIG. 15 is a perspective view of a third embodiment of a hose;
FIG. 16 is a rear elevation view of the hose shown in FIG. 15;
FIG. 17 is a front elevation view of the hose shown in FIG. 15;
FIG. 18 is a left side elevation view of the hose shown in FIG. 15;

FIG. 19 is a right side elevation view of the hose shown in
FIG. 15;

FIG. 20 is a top plan view of the hose shown in FIG. 15; and
FIG. 21 is a bottom plan view of the hose shown in FIG. 15.
FIG. 22 is a perspective view of a fourth embodiment of a
hose;

FIG. 23 is a rear elevation view of the hose shown in FIG. 22;
FIG. 24 is a front elevation view of the hose shown in FIG. 22;
FIG. 25 is a left side elevation view of the hose shown in FIG. 22;

FIG. 26 is a right side elevation view of the hose shown in
FIG. 22;

FIG. 27 is a top plan view of the hose shown in FIG. 22; and,
FIG. 28 is a bottom plan view of the hose shown in FIG. 22.
The broken lines shown in the drawings illustrate portions of
the hose that form no part of the claimed design.

The hose is shown with a symbolic break in its length. The
appearance of any portion of the hose between the break lines
forms no part of the claimed design.
